UNITED STATES PATENT OFFICE.

ERNEST DAVID, OF MAYWOOD, ILLINOIS, ASSIGNOR OF ONE-THIRD TO HERMAN KRAUS, OF CHICAGO, ILLINOIS.

POWER-OPERATED AIR-PUMP FOR AUTOMOBILES.

1,377,403.

Specification of Letters Patent.

Patented May 10, 1921.

Application filed April 8, 1920. Serial No. 372,143.

To all whom it may concern:

Be it known that I, ERNEST DAVID, a citizen of the United States, residing at Maywood, in the county of Cook and State of Illinois, have invented certain new and useful Improvements in Power-Operated Air-Pumps for Automobiles, of which the following is a specification.

This invention relates to pumps for inflating the tires of motor vehicles, and has reference more particularly to that type of air pump which is mounted on the motor vehicle itself and is adapted to be driven from the engine of the latter.

15 The main object of the present invention is to provide a simple, inexpensive and reliable air pump which may be readily attached to an element of the automobile frame and may be conveniently geared to a 20 moving element of the driving mechanism of the car in such a manner that it may readily be thrown into and out of driven relation to the motor.

Other objects are, to provide a pump 25 which may be readily detached or removed, when necessary; to provide a pump that shall not require lubrication; to provide a driving mechanism that can be operated directly from the engine shaft; to provide a 30 driving mechanism that can be thrown into and out of operation by the manipulation of a cam lever; and to provide certain detail improvements in the pump itself.

Still other objects and advantages of the 35 invention will be apparent to those skilled in the art as the same becomes better understood by reference to the following description, taken in connection with the accompanying drawings in which I have illustrated a practical and preferred embodiment of the invention and in which—

Figure 1 is a top plan view of my improved pump and of the parts of an automobile with which it is directly associated;

45 Fig. 2 is a longitudinal section through the pump cylinder and piston;

Fig. 3 is a transverse section on the line 3—3 of Fig. 2;

Fig. 4 is a transverse section of the pump 50 piston or plunger taken in a plane at right angles to that of Fig. 2;

Fig. 5 is a transverse section taken on the line 5—5 of Fig. 2;

Fig. 6 is a side elevation, partly in section, of the parts shown in Fig. 1; 55

Fig. 7 is a transverse section on the line 7—7 of Fig. 6; and,

Fig. 8 is a horizontal section of the combined drive pulley of the fan and pump.

Referring to the drawings, 10 designates 60 the engine shaft, 11 the fan shaft, 12 the fan, 13 and 14 the fan driving pulleys fast on the engine shaft 10 and the fan shaft 11, respectively, 15 the fan driving belt and 16 one of the channel side sills of the chassis 65 frame of a Ford car.

17 designates a bracket arm formed with an integral square shank 18 that fits within the channel side sill 16, being secured in the latter by a vertical through-bolt 19. In 70 order to hold the bracket arm 17 rigid against side play, set screws 20 and 21 are passed through the shank 18 on opposite sides of the vertical bolt 19, the inner ends of these set screws abutting against the vertical wall of the side sill 16.

Mounted on the bracket arm 17 by a horizontal pivot bolt 22 is a saddle 23 conveniently formed of thick sheet metal, the opposite sides of the saddle being cut to provide a pair of downwardly bent supporting arms 24 apertured at their lower ends to receive the pivot bolt 22, and two pairs of upwardly extending clamping arms 25 which embrace the pump cylinder and are drawn 85 together above the latter by clamp bolts 26. The metal of which the saddle 23 is formed is sufficiently flexible to enable the clamping arms 25 to be spread apart sufficiently for the passage of the cylinder between them 90 when the clamp bolts 26 have been removed.

27 designates the pump cylinder that is seated in the saddle 23, and, as best shown in Fig. 2, is threaded at its ends to receive cylinder heads 28 and 29. Cast integral 95 with the cylinder head 28 is an arm 30 in the outer end of which is journaled a shaft 31 on one end of which is a grooved pulley 32. On the opposite end of the shaft 31 is a crank arm 33 carrying a crank pin 34 engaged with the outer end of a piston-rod 35. The inner end of the piston-rod 35 is connected, by a pivot pin 36, to a pair of lugs 37 on the back of a metal piston disk 38, between which latter and a metal cup 39 is 100 clamped the piston cup-leather 40, the parts

38, 39, and 40 being united by a pair of screws 41 (Fig. 4). The opening 42 in the disk 38, formed by bending up the pivot lugs 37, communicates with an opening 43 in the cup-leather 40, and the opening 43 communicates with a central hole 44 in the metal cup 39. This hole 44 is covered by a disk check-valve 45 that is confined in working position by a keeper ring 46, formed with radial lugs 47 (Fig. 2) that are attached to the metal cup 39 by small screws 48. Leakage of air between the cylinder 27 and its head 29 is guarded against by an annular internal packing ring 49 of solder or like material.

The other cylinder head 28 is formed with a transverse slot 50 to accommodate the play of the piston-rod 35, and it is also provided, on opposite sides of the slot 50, with holes 51 in which latter are slidably mounted a pair of piston guide-rods 52 that are rigidly mounted at their inner ends in the piston, and serve to hold the latter against the tilting tendency caused by the alternate pushing 25 and pull of the swinging piston rod or pitman 35. On the cylinder head 29 is mounted a delivery nozzle 53 to which is attached a hose 54 of sufficient length to reach all of the four tires of the vehicle.

30 On the fan pulley 13, and preferably integral therewith and just forwardly thereof is a grooved pulley 55 that is connected by a belt 56 with the pump pulley 32. In order to tighten the belt 56 for driving the 35 pump, there is pivotally mounted at 57 (Fig. 6) on the free end of the bracket arm 17, a cam 58 that underlies the cylinder head 28, said cam being provided with an operating handle 59, and with a stop shoulder 40 60. When the cam is swung to the position shown in Fig. 6, the pump cylinder is rocked on its pivot 22 sufficiently to tighten the belt 56 and effect the actuation of the pump. Except when the pump is operating, it is necessary to interrupt the drive between the pulleys 55 and 32, and this is effected by means of a thrust bolt 61 slidably mounted in a countersunk hole in the bracket 45 17 and bearing against the cylinder head 29; the bolt being normally thrust upwardly by a compression spring 62 encircling it and confined between the head of the bolt and the bracket arm 17. Obviously, the normal tendency of the spring bolt is to 50 tilt the pump cylinder in a direction to slacken the belt 56, just as soon as the cam 58 is moved to idle position, which is effected by swinging the handle 59 to the left in Fig. 6.

60 For the exclusion of dust and dirt, the driving connections between the pulley 32 and the pump plunger are covered by a crank case or housing 63 shown in Figs. 1 and 6 which is mounted on the cylinder

head 28 by fastening screws 64 passed through a lip or flange 65 on the inner end of said crank case.

The mode of operation of the pump has been sufficiently indicated in connection with the description of its structure and organization to enable it to be readily understood. When the tires require inflation or compressed air is needed for any other purpose, the cam handle is swung to the position shown in Fig. 6, thereby establishing a power transmission from the engine shaft to the pump through the tightening of the belt 56. When the pump is no longer required, and the car is being driven, the controlling cam is in its inoperative position, the belt 56 is slack, and the pump is idle.

It is manifest that the details of construction herein shown and described may be variously modified without departing from the substance of the invention or sacrificing any of the advantages thereof. Hence, I reserve all such modifications as fall within the spirit and purview of the appended claims.

I claim—

1. In an air pump for automobiles, the combination of a bracket, means for attaching said bracket to a side sill of the chassis frame, a saddle pivotally mounted on said bracket, a pump cylinder removably mounted in said saddle and having a cylinder head formed with a rigid rearward extension, a shaft journaled in said extension, a crank on one end of said shaft connected to the piston rod of the pump, a pulley fast on the other end of said shaft, a driving pulley fast on the engine shaft, a belt connecting said pulleys, and manually operated means for tightening and slackening said belt.

2. In an air pump for automobiles, the combination of a bracket, means for attaching said bracket to a side sill of the chassis frame, a pump cylinder mounted on said bracket and formed with a rigid rearward extension, a shaft journaled in said extension, a crank on one end of said shaft connected to the piston rod of the pump, driving mechanism between the other end of said shaft and the engine shaft, and a crank case secured to the rear end of said cylinder and inclosing said crank and piston rod.

3. In an air pump for automobiles, the combination of a bracket, means for attaching said bracket to a side sill of the chassis frame, a saddle transversely pivoted on said bracket, a pump cylinder removably mounted in said saddle and formed with a rigid rearward extension, a shaft journaled in said extension, a crank on one end of said shaft connected to the piston rod of the pump, a pulley fast on the other end of said shaft, a driving pulley fast on the engine shaft, a belt connecting said pulleys, and a manually operated cam for rocking

said saddle on its pivot whereby to bodily shift said first named pulley away from said driving pulley whereby to tighten said belt.

4. In an air pump for automobiles, the combination of a bracket, means for attaching said bracket to a side sill of the chassis frame, a saddle transversely pivoted on said bracket, a pump mounted in said saddle and formed with a rigid rearward extension, a shaft journaled in said extension, a crank on one end of said shaft connected to the piston rod of the pump, a pulley fast on the other end of said shaft, a driving pulley fast on the engine shaft, a belt connecting said pulleys, a compression spring between said bracket and one end of said pump tending to rock the latter in a direction to

slacken said belt, and a manually operable cam between said bracket and the other end of said pump serving to rock the latter in a 20 direction to tighten said belt.

5. In an air pump for automobiles, the combination with a pump cylinder, of a bracket for supporting the same from the channel side sill of a chassis frame, said 25 bracket having a shank fitted within said channel side sill, a vertical bolt passed through said side sill and shank, and set-screws passed through said shank and abutting against the vertical wall of said side 30 sill on opposite sides, respectively, of said vertical bolt to hold said bracket against lateral movement.

ERNEST DAVID.
